UNITED STATES PATENT OFFICE

2,609,122

DENTIFRICE CABINET

Patrick J. Stenerson, Fernwood, Idaho

Application May 16, 1950, Serial No. 162,337

3 Claims. (Cl. 222—105)

1

This invention relates to a dentifrice cabinet and it is one object of the invention to provide a cabinet which is adapted to be mounted against a wall in a bath room and serve as a container for a bottle of liquid dentifrice and also as a container for a tube of tooth paste. While it has been stated that the tube holds tooth paste and the bottle contains liquid dentifrice it will be understood that the tube may contain shaving cream and the bottle be filled with shaving lotion or the tube and the bottle may contain other substances.

Another object of the invention is to provide a cabinet having a hood which is removably supported upon a base, the base being adapted to support tooth brushes and protect them from exposure to dust.

Another object of the invention is to provide the base with improved means for supporting the tube and the bottle in an upright position in which they are inverted so that their contents may be discharged onto tooth brushes held under the base and directly below outlets of the tube and the bottle.

Another object of the invention is to provide a base having threaded openings formed through it to receive adaptors into which the neck of a tube and a bottle are screwed so that the tube and the bottle will be removably supported in the upright inverted position, a closure plate for the adaptor carrying the tube being carried by the base and the adaptor for holding the bottle being provided with a dispensing valve and with means for admitting air into the bottle as liquid is discharged therefrom.

The invention is illustrated in the accompanying drawings wherein:

Fig. 1 is a perspective view of the improved cabinet.

Fig. 2 is a transverse vertical sectional view taken along the line 2—2 of Figure 1.

Fig. 3 is a transverse vertical sectional view taken along the line 3—3 of Figure 1.

Fig. 4 is a horizontal sectional view taken along the line 4—4 of Figure 3.

Fig. 5 is a sectional view showing a modified construction.

This dentifrice cabinet has a base 1 which may be formed of metal, or other suitable material, and defines a flat rectangular platform 2 having a depending flange 3 along its front edge and side edges. A wall 4 extends downwardly across the rear edge of the platform and is formed with openings 5 to receive screws. Braces 6 extend forwardly from ends of the rear wall and merge

2

into rear ends of the flange 3 so that the platform will be prevented from bending downwardly out of a horizontal position. A recess 7 is formed along marginal edges of the platform to receive lower edge portions of the walls of a hood 8 and prevent the hood from slipping out of its proper position when placed upon the base. Therefore the hood may be readily removed from the base but it will not be liable to accidentally slip off of the base. Longitudinally spaced openings 9 are formed through the base adjacent the front edge thereof and are of such size that the handles of tooth brushes may be passed downwardly through the openings and the heads thereof supported upright above the base. One brush 10 has been shown to be so supported in Figure 1 and it will be understood that additional brush-receiving openings may be formed in spaced relation to end edges of the base if so desired.

20 In order to removably support a tube 11 and a bottle 12 in an inverted upright position the base has been formed with depending bosses 13 and 14 which are threaded internally so that adaptors 15 and 16 may be screwed downwardly into the bores 25 of the bosses and project above and below the platform of the bodies of the base. Upper portions of the adaptors are enlarged to form sockets which limit downward movement of the adaptors, through the bosses and these sockets are internally threaded to receive the threaded necks 11' and 12' of the tube and the bottle. Diametrically opposed apertures 17 are formed through front and rear portions of the boss 13, and in alignment with these apertures adaptor 15 is provided with 30 openings 15'. The portion of the flange 3 along the front edge of the platform is formed with an aperture 18 aligned with apertures 17 and openings 15' so that a transversely positioned plate or strip 19 may be slidably passed therethrough and moved into and out of position for an opening 20 35 in the strip to register with the bore of the adaptor. The outer end portion of the strip is bent downwardly and forms a handle 21 by means of which the strip may be readily grasped and the strip slid transversely to an opened or 40 closed position. A tongue 22 which is cut from the strip and extends longitudinally towards the front end thereof is bent downwardly forming a stop which serves to limit transverse outward movement of the strip and prevents the strip from being drawn outwardly too far. Since the strip is formed of resilient material the tongue may be urged upwardly during insertion of the strip and then return to its downwardly inclined 45 position. The fact that the tongue is resilient 50

also allows it to be pressed upwardly to a position in which it will enter the opening and allow complete withdrawal of the strip for thorough cleaning. When tooth paste in the tube is to be used the strip is shifted transversely and the cover or hood 8 removed. It is then merely necessary to place a tooth brush under the lower end of the adaptor 15 and apply pressure to the tube for forcing tooth paste out of the tube and through the adaptor onto bristles of the tooth brush.

The adaptor 16 into which the neck of the bottle is screwed is formed about the bottom of its socket with an internal ledge 16' upon which a gasket rests in order to form a liquidtight joint and prevent leakage of liquid from the inverted bottle. At its lower end adaptor 16 is formed with an internal flange or valve seat 23 upon which rests a valve disc 24 carried by a tube or hollow stem 25. This tubular stem extends vertically in the adaptor and the bottle, with its upper end spaced downwardly from the upwardly disposed bottom of the bottle and its lower end portion projecting downwardly from the lower end of the adaptor. A helical spring 26 surrounds the stem with its lower end resting upon the valve disc and its upper end abutting the under face of the ledge 16'. The spring urges the valve disc and the tube downwardly so that the disc is normally in sealing engagement with the valve seat 23. When the tube is pressed upwardly liquid dentifrice or other liquids in the bottle may flow downwardly through the adaptor and outwardly about the disc and the tube and onto a tooth brush held under the tube and employed as means for forcing the tube upwardly. It will be evident that if the bottle contains an aftershave lotion a finger of a hand held under the adaptor may be employed to force the tube upwardly and the lotion will be caught in the palm of the hand. Since the stem 25 is a tube open at both ends air may flow upwardly through the tubular stem and into the bottle above the level of liquid therein and thus allow the liquid to flow freely from the bottle.

In Figure 5 there has been shown a modified construction wherein the boss 26 which takes the place of the boss 13 is formed with a rear extension 27 formed with a socket 28 into which slidably fits the rear end portion of the closure plate or strip 19. This strip has been indicated by the number 19 as it is the same strip shown in Figure 3 and other elements of Figure 5 which are the same as those shown in Figure 3 are indicated by corresponding numbers. The adaptor 29 which takes the place of the adaptor 15 is shorter than the adaptor 15 and has its lower end terminating level with the upper wall of the socket 28 so that the upper surface of the closure plate has close fitting engagement with the lower end of the adaptor and forms a tight closure for the adaptor when the strip is pressed inwardly to its closed position. When the strip is drawn outwardly to the opened position the opening 20 of the strip registers with the lower end of the bore of the adaptor and tooth paste may pass through the opening 20 and onto the bristles of a brush held under the adaptor. A pin 30 mounted vertically through the strip takes the place of the abutment tongue 22.

Having thus described the invention, what is claimed is:

1. A dentifrice cabinet comprising a base constituting a shelf and formed with a downwardly extending boss having a threaded bore open at

upper and lower ends, a depending flange along a front edge of the shelf formed with an opening opposite the front portion of said boss, the boss being formed with transversely positioned opposed front and rear openings aligned with the opening in said flange, a hollow adaptor screwed into the bore of said boss and open at upper and lower ends and formed in front and rear portions with openings registering with the openings in the boss, said adaptor adapted to support a container in an inverted vertical position, and a flat strip transversely slideable through the aligned openings of the flange and the boss and the adaptor and formed with an opening, the outer end of said strip being bent downwardly and forming a handle for sliding the strip transversely from a closed position in blocking relation to the hollow adaptor to an opened position in which its opening registers with the adaptor for allowing flow of material downwardly through and out of the adaptor.

2. A dentifrice cabinet comprising a shelf having a longitudinally extending front edge formed with a depending flange having an opening, a boss extending downwardly from said shelf and formed with a threaded bore open at upper and lower ends, the boss being formed with transversely positioned openings aligned with the opening in said flange, a hollow adaptor screwed into the bore of said boss and open at its upper and lower ends and adapted to support a container, the lower end of said adaptor terminating at the openings in said boss, a closure strip, slideable transversely of the shelf through the opening in said flange and through said boss transversely thereof into and out of a position for blocking the open lower end of the adaptor, said strip having an end portion projecting forwardly from the flange and constituting a handle for the strip, and a tongue cut from a portion of the strip under the shelf and constituting an abutment extending longitudinally of the strip and free at its front end and bent downwardly into position for engaging the rear face of the flange and limit forward movement of the strip.

3. A hollow adaptor for a dentifrice cabinet having a shelf with a depending apertured flange formed at its front edge and an internally threaded hollow apertured boss extending downwardly from said shelf, said apertures being aligned transversely of the shelf, comprising a body having an enlarged upper portion for limiting its downward movement in said boss, an externally threaded portion for threading into said boss and positioned below said upper portion, said upper portion internally adapted to receive and support a container in an inverted vertical position to permit flow of material from the container downwardly through the adaptor, diametrically opposed openings in said threaded portion adapted to be aligned with the apertures of said boss and flange, a reciprocable closure strip in the openings adapted to slide through the aligned openings and apertures, an opening in said strip movable into and out of registry with the hollow adaptor, said strip adapted to normally block the hollow adaptor when its opening is out of registry therewith, said strip adapted to project through the aperture of said flange and having an end portion bent downwardly and constituting a handle for the strip, and a tongue cut from a portion of the strip and constituting an abutment extending longitudinally of the strip and free at its front end and bent downwardly into position adapting it for

engagement with the rear face of the flange to limit movement of the strip.
